H. M. LUND

JAVELIN STICK AND METHOD OF MAKING THE SAME

Filed Jan. 5, 1924

Patented Sept. 8, 1925.

1,552,442

UNITED STATES PATENT OFFICE.

HENRY M. LUND, OF BROOKLYN, NEW YORK.

JAVELIN STICK AND METHOD OF MAKING THE SAME.

Application filed January 5, 1924. Serial No. 684,526.

To all whom it may concern:

Be it known that I, HENRY M. LUND, a citizen of Norway, and residing at Brooklyn, in the county of Kings and State of New York, have invented certain new and useful Improvements in Javelin Sticks and Methods of Making the Same, of which the following is a specification, such as will enable those skilled in the art to which it app pertains to make and use the same.

This invention relates to javelin sticks and particularly to the method of manufacturing sticks of this class; and the object of the invention is to provide an improved method of producing sticks of the class specified whereby such sticks are rendered stronger and more durable in use; and with these and other objects in view, the invention consists in a device of the class specified, constructed as hereinafter described and claimed.

The invention is fully disclosed in the following specification, of which the accompanying drawing forms a part, in which the separate parts of my improvement are designated by suitable reference characters in each of the views, and in which:

Fig. 1 is a side view of a javelin stick made according to my invention and with part of the construction broken away and in section.

Fig. 2 is a transverse sectional view, showing the first step in the making of my improved stick.

Fig. 3 is a cross sectional view of the stick formed from the structure shown in Fig. 2; and,

Figs. 4 and 5 are views similar to Fig. 3 but showing modified forms of construction.

In the manufacture of javelin sticks according to the present methods of procedure, a strip of hickory, ash, or other hard wood, is fashioned to form the shank of the javelin stick, and by reason of the fact that the shank of the stick is composed of a single piece of wood of the kind specified, it has been found in practice, that a javelin stick so made is readily subject to breakage. It is oftentimes experienced that a new javelin stick after it has been thrown one or two times by an athlete, will break, thus putting the athlete or athletic association to considerable expense in the replacement of broken javelin sticks.

The sole object of my invention is to so construct a javelin stick as to increase the

strength and durability thereof, and in carrying my invention into effect, I provide as shown in Figs. 1 to 3 inclusive, two elongated and rectangular strips 10 and 11 of a suitable wood or combinations of suitable wood, such for example as hickory, ash, or the like, and the strips 10 and 11 are placed side by side and glued or otherwise joined together as shown at 12 to form an elongated bar 13 rectangular in form in cross section and composed of the separate strips of wood 10 and 11.

The bar 13 when formed as above described, is now fashioned by hand or in a suitable machine to substantially circular formation in cross section as shown at 14 in Fig. 3 of the drawing, and from the point 15 substantially centrally of the bar, said bar is tapered to a slight extent toward the end 16 thereof and to a greater extent toward the end 17 thereof as clearly shown in Fig. 1 of the drawing. The wood portion or shank of the javelin stick is now made and is ready for insertion into a metallic pointer or spear 18 having a tapered socket 19 into which the end portion 16 of the javelin stick is adapted to be placed and secured.

According to the present practice, the end portion of the javelin stick is secured to the pointer or spear by tacks, nails, rivets or the like, which renders the wood portion of the javelin stick weak, and subject to breakage in addition to the general weakness of the stick by reason of the method of its manufacture. In practice, I secure the tapered end 16 of my improved javelin stick to the pointer 18 by fashioning the pointed end 16 of the stick to provide a taper thereon which is larger in diameter than the diameter of the bore 19 in the pointer, when said pointer is under normal temperature. In securing the parts together or the pointer 18 to the stick or shank thereof, the pointer 18 is heated in any desired manner to expand the metal thereof and when expanded the stick or end portion 16 is inserted into the bore 19 and the pointer 18 is chilled in the usual manner, which automatically shrinks the metal of the pointer or returns it to normal position and the stick is thus rigidly retained in the bore 19 of the pointer. It will be understood that in the above operation, the pointer 18 is not heated to a degree sufficient to burn or char or effect in any way the wood of the stick or that por-

tion thereof inserted into the bore 19 of the pointer. The shank of the javelin stick may be removed from the pointer by simply reversing the above operation; namely, first 5 heating the pointer 18 until it has expanded sufficiently to permit of the extraction of the stick as will be apparent.

It must be borne in mind that the shank 10 of the javelin stick or the wood portion of the stick is, at its largest diameter, approximately one inch, and by reason of the fact that the entire length of the stick or the wood portion thereof is eight feet or over, it must be readily understood that when the 15 stick is composed of a single piece of wood, the same will readily break when subject to the strains which prevail in the sport, and by constructing the shank of the stick of two pieces of wood, and arranging the 20 grains of the separate pieces to provide the greatest strength, it has been found in actual practice and experience that a much stronger javelin stick is produced and one which is very durable in use.

25 In Fig. 4 of the drawing, I have shown the shank of a javelin stick composed of three strips of wood 20, glued or otherwise secured together as shown at 21, while in Fig. 5 of the drawing, I have shown the 30 shank of the stick composed of four independent strips of wood 22 secured together as shown at 23. It will be apparent that the stick may be composed of two or more strips of wood of the same grade of wood, 35 or of different grades of wood, as the case may be, and while I have referred to specific classes of wood, it will be understood that I am not limited in this respect, nor am

I limited to the specific shape of the javelin stick or the wood shank thereof shown and described, nor to the shape or construction of the metallic pointer shown and described, and various changes in and modifications of the construction herein shown and described and the method 40 set out may be made within the scope of the appended claims without departing from the spirit of my invention or sacrificing its advantages.

Having fully described my invention, 50 what I claim as new and desire to secure by Letters Patent, is:—

1. The herein described method of manufacturing javelin sticks which consists in 55 fashioning the shank of the stick of two or more independent strips of wood, securing said strips together, fashioning said strips to produce a shank of the desired form, and securing a metallic pointer to one end of the shank formed from said strips by heating 60 said pointer to expand the metal thereof to permit of the insertion of one end of the shank into said pointer.

2. The herein described method of manufacturing javelin sticks which consists in 65 fashioning an elongated body of wood to form a bar tapered at its end portions, securing a metallic pointer to one end of the bar by heating said pointer to expand the metal thereof to permit the insertion of one 70 end of the bar into said pointer.

In testimony that I claim the foregoing as my invention I have signed my name this 2nd day of January 1924.

HENRY M. LUND.
